UNITED STATES PATENT OFFICE.

FREDERICK H. GROSS AND ELWOOD GROSS, OF PLYMOUTH, PENNSYLVANIA.

MINER'S SQUIB.

SPECIFICATION forming part of Letters Patent No. 693,964, dated February 25, 1902.

Application filed October 4, 1901. Serial No. 77,694. (No model.)

To all whom it may concern:

Be it known that we, FREDERICK H. GROSS and ELWOOD GROSS, citizens of the United States, residing at Plymouth, in the county 5 of Luzerne and State of Pennsylvania, have invented a new and useful Miner's Squib, of which the following is a specification.

This invention relates to miners' squibs.

The object is to present a squib the construction of which will render it absolutely safe in use and which will be thoroughly reliable and certain of operation; furthermore, to present a squib having a novel form of closure for the end of the tube, whereby in 15 the event of inclusion of grains of powder in the match the explosion of the same will not operate to set off the squib, thereby obviating the necessity of the miner having to untwist the match to ascertain if there be 20 any powder included therewith.

With these and other objects in view, as will appear as the nature of the invention is better understood, the same consists in the novel construction and combination of parts of a 25 miner's squib, as will be hereinafter fully described and claimed.

In the accompanying drawings, forming a part of this specification, and in which like numerals of reference indicate corresponding 30 parts, there is illustrated one form of embodiment of the invention capable of carrying the same into practical operation, it being understood that the elements therein exhibited may be varied or changed as to shape, 35 proportion, and exact manner of assemblage without departing from the scope of the invention and in these drawings.

Figure 1 is a view in plan, exhibiting the squib-blank as it appears before being rolled 40 to present a squib. Fig. 2 is a similar view exhibiting the first step preparing the blank for formation into a tube. Fig. 3 is a similar view showing the second step. Fig. 4 is a similar view showing the third step. Fig. 5 45 is a similar view showing the fourth step. Fig. 6 is a perspective view exhibiting the finished squib-blank with the needle and mandrel still in position therein.

Referring to the drawings, 1 designates generally the squib-blank, comprising a body portion 2, a closing-flap 3, and a match 4.

All of these parts are integral, and the blank is to be made, preferably, of paper.

The body 2 of the blank, in this instance shown approximately trapezoidal in shape, 55 although, if preferred, it may be of other contour, is provided on one side with a flap or lip 5, formed by cutting away a portion of the forward end of the blank, as at 6. The portion of the blank constituting the match 60 4 is produced by an extension 7, divided into two parts by an incision 8, an incision 9, terminating approximately in line with the shoulder 10 of the flap 5, serving to make the two match members of approximately the same 65 length. The closing-flap 3 is produced by an approximately rectangular extension of the body, which by a plurality of incisions 11 produce fingers 12, that by being pasted together and rolled inward over the needle or 70 mandrel 13 present a closure for the forward end of the tube. The form of closing-flap herein shown has been found effective in use and will generally be adopted; but it is to be understood that the invention is not to be 75 limited to the exact shape thereof herein shown, as it will be obvious that the same may be otherwise contoured, if found necessary or desirable, and still be within the scope of the invention. The incisions 11, that produce the fingers 12, are herein shown as radially disposed, this disposition being employed on account of the shape of the closing-flap; but should the said flap be square the 80 incisions will then be disposed approximately 85 parallel with the side of the body of the blank on which the flap is located.

In the formation of the squib-tube the base of the closing-flap is folded down and pasted to the body of the tube, as shown at 14, thereby presenting two tongues 15 formed by the outer portion of the blank-body and the inner portion thereof adjacent to one of the tongues. The needle or mandrel is then laid upon the blank, as shown in Fig. 3, with the end contiguous to the base of the flap 3; and the side of the blank adjacent to the flap is then rolled around the mandrel, as shown in Fig. 4, the tongues 15 projecting outward and being aggregated with the tongues of the closing-flap, 90 these latter tongues being then securely assembled by some adhesive material to effect 95 100

closing of the outer end of the squib-tube, and the rolling is then continued until the entire body of the blank is rolled around the mandrel, a layer of adhesive material (indicated by 16) on the lip 5 serving to hold the blank in its rolled disposition. When the squib-tube is thus formed and prior to the twisting of the match members, as shown in Fig. 6, the outer end of the tube will, as before stated, 10 be closed by the fingers forming the closing-flap and by the two tongues 15, these all being secured together by some suitable adhesive material, so as to present a multi-ply structure at the end of the tube, which will 15 be thoroughly effective to prevent explosion of the squib should powder explode thereon. The match members are finally twisted together, as shown in Fig. 6, and may be treated with any suitable substance to render them 20 certain of ignition and burning. The mandrel is now removed and the squib-tube filled with powder in the usual manner and sealed. It will be observed that where the match members merge into the squib-body there is 25 only a single thickness of paper, so that all danger of the match failing to ignite the squib will be prevented. Moreover, as the tongues diverge from the twisted portion there are in reality two matches presented, which will 30 double the chance of the squib being properly ignited.

It will be seen from the foregoing description that by the manner of sealing the end of the squib-tube all danger of the squib being 35 prematurely exploded, as by grains of powder,

der being exploded thereon, will be effectively obviated, so that a miner need feel no apprehension of danger in using the same and will be indifferent whether powder is included within the match or not. Further, by the provision of two matches certainty of ignition of the squib will be insured. 40

Having thus fully described our invention, what we claim as new, and desire to secure by Letters Patent, is— 45

1. A miner's squib having its match ends sealed by a closure composed of a plurality of fingers assembled by a suitable adhesive material.

2. A miner's squib having two match members disposed on opposite sides of the squib-tube and separated at their point of juncture therewith, and a closure for sealing the match end of the tube, comprising a plurality of fingers permanently assembled by a suitable 50 adhesive material.

3. As a new article of manufacture, a blank for miners' squibs, comprising a body portion carrying at one end two tongues to constitute the match members, and a plurality of fingers adjacent to the base of the tongues to be assembled to constitute a closing-flap. 55

In testimony that we claim the foregoing as our own we have hereto affixed our signatures in the presence of two witnesses.

FREDERICK H. GROSS.
ELWOOD GROSS.
